E. W. SPACKMAN

ELECTRIC HEATER

Filed March 23, 1925

Fig. 4.

INVENTOR,
Earl W. Spackman,
By Joseph A. Mietura
Attorney.

UNITED STATES PATENT OFFICE.

EARL W. SPACKMAN, OF INDIANAPOLIS, INDIANA.

ELECTRIC HEATER.

Application filed March 23, 1925. Serial No. 17,579.

My invention relates to means for heating and circulating air by an electrically heated element and it is the primary object of my invention to provide such electric heating means in a form whereby the most effective transfer of heat to the room to be heated is had with the lowest possible cost of operation.

In accomplishing such an object, it is my purpose to provide the electric element in a form adapted for use in either a portable stove for carrying from one room to another, a fixed stove, or a furnace of the full circulating air type now in common usage and well known construction.

All electric heating devices that I am aware of depend upon conduction or radiation and not upon convection. It is well known that in heating a space occupied by persons, that less heat is required and more comfort is secured when the air within that space is moving and not stationary. My device heats the air in the space by convection, depending entirely upon the circulation of the air to convey the heat to the space desired.

A further purpose of my invention is to provide a low-temperature heating element whereby the oxygen and moisture in the air current is not diminished such that a more healthful atmosphere is created.

Minor objects lie in the feature of interchangeability of the electrical heating unit with old types of heating units, the simplicity of construction, the cheapness of production, the extreme durability and the easy control of the heat.

I accomplish these and such other objects as may be apparent in the accompanying description, by the means as shown in the accompanying drawing, in which—

Fig. 1 is a top plan view of my electrical heating unit; Fig. 2, a vertical section of the heating unit taken on the line 2—2 in Fig. 1; Fig. 3, a side elevation of an individual element of the heating unit; Fig. 4, a wiring diagram of the heating unit; Fig. 5, a portable stove with fragments removed; and Fig. 6, a diagrammatic view of a furnace employing my heating unit.

Like characters of reference indicate like parts throughout the several views.

I form a supporting base by joining the two bars 8 by the end pieces 9. The individual elements 10, as shown in Fig. 3, are

spaced apart and rest on the bars 8, as in Figs. 1 and 2, and are there secured by the top bar 11 bearing on the top edges of the elements 10 and secured by each end to the end pieces 9. I have here shown the elements 10 to be five in number to make the complete unit, but this number may be varied to meet the required amount of heat desired. I have also shown one form of holding the elements 10 by means of the slots 65 formed in the bars 8 and the top bar 11 and clamping the elements therebetween. This structure may be varied to assume a number of forms. The principal feature is that the elements 10 be held vertically and spaced 70 apart to define flues of substantial height between for the upward passage of air.

Each element 10 is made of a non-conducting material, preferably porcelain, and carries on its lower section, the resistance wire 75 12 of such length and diameter that with the circuit employed, the wire 12 will at no time be so hot as to have even a visible red color. I employ a simple circuit as indicated in Fig. 4 where the elements are all in 80 parallel, when no intermediate heat control between the on and off conditions is wanted. To effect such an intermediate control, the diagram may be varied to place part or all of the elements 10 in a series and parallel 85 circuit with the proper switch control in the usual and well known manner of so regulating the flow of electricity.

The wires leading from the elements 10 are brought to the terminals 13, Fig. 2, from 90 which wires may be led to the control switch 14 such as is indicated in Fig. 5.

The unit as shown in Fig. 1 is so formed as to fit readily with a circular housing 15 such that a column of air of appreciable height is 95 defined within and above the unit. As the unit is entirely open at the bottom except for the supporting bars 8 and 9, and the top of the housing 15 is also open, being covered in the usual manner by an open or perforate 100 grate, a current of air will flow through the housing 15 as indicated by the arrows, Fig. 5, being induced and set in motion by the heated elements.

In Fig. 6, a diagram of a heating plant is 105 shown where the cold air is taken off the floor 16 of a room through a cold air shaft 17 leading to the bottom of the heater 18, thence upwardly through the electrical heating unit between the elements 10, and out 110

the conducting pipe 19 and back into the room to complete the circuit of the air current.

It will be noted that the air is set in motion by means of first heating a plurality of small columns of air and that as the air continues to move it carries the heat by convection to the room desired to be heated. No dependence is placed upon an incandescent body radiating heat. Further attention is called to the fact that by confining the resistance wires 12 to a comparatively limited space at the lower end of each element, and to the proximity of the wires 12 on the adjacent element, the amount of heat is concentrated or "built up" so as to be most effective in setting the air in motion. As the wires are kept at comparatively low temper-

atures the total effective heat would be less, were the wires spread out over the element or otherwise more widely separated.

I claim:

In an electric heater, a housing having an appreciable height and having openings at the bottom and at the top, and a portable electrical heating element adapted to be positioned within the lower end of the housing, said heating element comprising a frame, a plurality of plates removably clamped in the frame defining passages therebetween, and a winding of resistance wire concentrated near the end of each of the plates nearest the intake openings of the housing.

In testimony whereof I affix my signature.

EARL W. SPACKMAN.
